DESIGN FOR A HAT STEAMER

Ray C. Utley and Arthur Feilchenfeld, Jr.,
Chicago, Ill.

Application March 1, 1943, Serial No. 109,644

Term of patent 14 years

To all whom it may concern:

Be it known that we, Ray C. Utley and Arthur Feilchenfeld, Jr., both citizens of the United States, residing in Chicago, county of Cook, State of Illinois, have invented a new, original, and ornamental Design for a Hat Steamer, of which the following is a specification, reference being had to the accompanying drawing, forming part thereof.

In the drawing, Figures 1, 2 and 3 are, respectively, a side view, an end view and a top view of a hat steamer embodying our new design.

We claim:

The ornamental design for a hat steamer, as shown.

RAY C. UTLEY.
